UNITED STATES PATENT OFFICE.

EMILIE SULLIVAN, OF LOS ANGELES, CALIFORNIA.

HEMMING DEVICE.

Application filed May 23, 1921. Serial No. 471,907.

To all whom it may concern:

Be it known that I, EMILIE SULLIVAN, a citizen of the United States, and a resident of Los Angeles, in the county of Los Angeles 5 and State of California, have invented new and useful Improvements in a Hemming Device, of which the following is a specification.

My invention relates to improvements in 10 a device for hemming fabrics of different kinds whereby the fabric may be firmly but slidably held and also, upon the completion of a certain predetermined linear stretch of hemming, the device may be easily moved 15 to the next consecutive stretch to be worked on.

It is an object to provide a device which shall hold a fabric firmly, but detachably and slidably, whereby a predetermined 20 amount of the fabric to be hemmed shall protrude from the holding portions of the device.

Another object is to provide a device that may be positioned on a fabric by a simple 25 motion, thereby holding the fabric firmly and allowing a predetermined amount of the fabric to be exposed to be hemmed.

Another object is to describe a device of 30 such simple structure that it may be made quickly and economically out of a one-piece stamping of metal.

With these, and other objects in view, and with reference to the drawings in which like 35 numbers indicate the same parts, it will be seen that—

Fig. 1 is a perspective view of my device.

Fig. 2 is a view of my device from above.

Fig. 3 is a section along the line A—A.

Fig. 4 is a section along the line B—B 40 showing a piece of fabric folded and in a position for hemming.

1 and 2 are the sides or holding members of the device, held in predetermined resilient spacing by spring means 3 and 4, which in 45 this case consist of loops of metal integral with 1 and 2.

1, apart from the loops, is a flat strip of material, and 2 is extended beyond the 50 length of 1 by flaps or ears 5 and 6 which are bent outwardly from the dividing line between 1 and 2 and back toward each other thus forming guides for the ready engagement of fabric to be held between 1 and 2.

A further guide for the engagement of 55 fabric is provided by turning the lower edge of 2 outwardly from the dividing line be-

tween 1 and 2 and slightly in an upward direction, in order to form a slight roll on the lower edge of 2.

This roll 7, together with flaps or ears 5 and 6 are provided to allow quick and easy engagement of the device on any fabric without permitting the thread of the fabric to become entangled or torn.

8 is a button or raised portion, stamped 65 or fastened on to side 2 for the purpose of moving the device along the edge of a fabric when a predetermined amount of hemming has been done thereon.

9 shows a piece of fabric firmly but slidably held between 1 and 2 and folded in the general position in which hemming is accomplished, and showing the two edges 19 and 20 which are to be hemmed by needle 10.

The operation is as follows:—

The fabric to be hemmed is folded substantially in the form as shown in Fig. 4 80 and having the edges 19 and 20 to be joined together.

One end of the folded fabric is then held by the thumb and forefinger of the left hand and the other end is held between the third and fourth fingers and the palm of the right hand, the distance between the ends being of sufficient length to accommodate the device, which for practical purposes I find to be about three inches long, the device being held between the thumb and forefinger of the right hand.

The folded fabric is held rigid and horizontal, as is also the device with flaps or ears pointing upwardly, and then flap 5 is pressed down and pushed in on the fabric whereby 1 and 2 are sufficiently sprung 95 apart to allow entrance of the fabric therebetween.

The entry having been started at an angle to the edge of the fabric, the engagement is completed by pushing the device forward and the rear end at 6 inwardly when roll 7 permits the device to slide easily over the fabric, so that the final position of engagement is that the edge of the fabric is 100 parallel to the edges of 1 and 2 and protruding from the recessed portion between 3 and 4 a distance equal to the height of these loops.

In practice I find this height to be about 110 $\frac{1}{16}$ of an inch which gives ample room for the hemming stitches and at the same time does not allow the material to sag outside

of sides 1 and 2, but I do not limit myself to this height as it may be varied to suit the material when my device is made in various sizes, but an outstanding feature of 5 my invention is that the height or depth of the loops or spring holding means determines the amount of fabric which shall protrude from the holding sides for the purpose of being hemmed, and also the distance between loops determines the amount of fabric 10 to be hemmed before moving the device along to a new position.

If it be assumed that hemming is being done, starting at loop 4 and working toward 15 loop 3, upon reaching loop 3 all that it is necessary to do in order to obtain a new predetermined position on the edge of the rolled fabric is to pass needle 10 through the fabric as shown in Fig. 4, and then press 20 slidably on flaps 5 or 6 or button 8 in the direction of 3 from 4 until the forward face of loop 4 is engaged with needle 10, thus limiting the advance of the device to a predetermined distance, which is the 25 length of the recessed portion between loops 3 and 4.

It will thus be seen that flaps 5 and 6 not only aid in engaging the fabric but also, according to the custom or habit of

the user, may be used to move the device 30 when engaged.

Sides 1 and 2 are preferably made parallel in the small sizes of my invention for fine fabrics, but in the large sizes they may converge slightly toward the lower edges so 35 that they will be parallel upon the engagement of thick fabric therebetween.

Loops 3 and 4 may be made of circular or other cross section, or any desired shape so 40 that they form resilient and efficient holding means between 1 and 2.

What I claim as new and desire to secure by Letters Patent is:—

Clamping means for holding a fabric 45 to be hemmed comprising a one-piece stamping of metal adapted to have a central portion cut out and to be folded so that it forms two holding strips integrally and resiliently connected by loops, one of the strips having means for engaging the fabric 50 curved away from the central plane between the two strips.

In witness whereof, I have signed my name in the presence of two witnesses.

EMILIE SULLIVAN.
